J. DOPYERA

BANJO

Filed Dec. 12, 1923

UNITED STATES PATENT OFFICE.

JOHN DOPYERA, OF TAFT, CALIFORNIA.

BANJO.

Application filed December 12, 1923. Serial No. 680,145.

This invention relates to banjos, and the main object is to provide an improved type of musical instrument in the form of a banjo having means for improving and 5 substantially amplifying the tone produced by the instrument by the provision of a resonator suitably supported on the bottom of the instrument, so as to take up the vibration, together with means for enclosing the 10 resonator in order to prevent the same coming in contact with other things while the instrument is being played.

Another object is to provide a banjo comprising a band for supporting a skin of 15 usual character, and a metallic covering on the opposite side of the band from the skin serving as a support for and enclosing a metallic resonator adjustably mounted for amplifying and substantially improving the 20 tone of the instrument.

Still another object consists in means provided for supporting the resonator on the band by the utilization of the usual skin holding devices whereby the resonator and 25 the cover may be detachably held in position.

Other objects will appear as the description progresses.

I have shown in the accompanying drawings a preferred embodiment of my invention, subject to modification within the 30 scope of the appended claims without departing from the spirit thereof, in which:

Fig. 1 is a composite plan view of my device, the upper portion of which is a top plan, the lower portion a bottom plan, and the intermediate portion a sectional plan.

Fig. 2 is a side view of the same, partly in section.

Fig. 3 is a perspective view of one of the holding devices for detachably supporting the resonator and cover on the band.

Fig. 4 is a fragmentary section of the cover, showing a modified structure.

In the consideration of this invention it 45 will be understood that my improvements are adapted to be attached to a modern type of banjo, or the same may be built into new instruments as may be desired.

In the drawings I have shown a well 50 known type of instrument which includes the usual supporting band B, usually made of wood and over the upper edge of which a skin S is firmly attached and held taut by 55 means of a plurality of adjusting screws A, A, etc. The outer edges of the skin S are

usually wrapped around an annular band b and are thence turned upwardly against the inner side of a substantially wider annular band b' which encompasses the main band B. The band b is thus held underneath the larger band b', and both of said bands are drawn downwardly with the edge portion of the skin S by means of the adjusting screws A, A, which have their upper ends e, e, etc., formed into hooks which overlie the upper edge of the band b'.

The lower ends of the screws A, A carry adjusting nuts N, N, etc., by means of which the skin is adjusted over the edge of the band B. The screws A, A, etc., are threaded at their lower ends to receive the nuts N, N, etc., and above said nuts they extend through lugs L, L, etc., which are supported on the outer side of the band B and are held against vertical movement thereon by means of screws l, l, etc., which have their heads on the inner side of band B and are threaded at their outer ends into the lugs.

The parts hereinbefore mentioned are embodied substantially in the relations stated in banjos now in vogue, and to said parts I apply my improvements in the manner hereinafter stated.

Said improvements consist of two main members, namely, a cover C which is of substantially greater diameter than the band B and which is adapted to receive and adjustably support a resonator R. The cover C is of thin sheet metal and has its edge portions rolled as at 2 into a hollow bead encompassing the lower portion of band B and terminating in an annular portion 3, the inner edge of which is spaced from the band B.

The central portion of the cover C underlies and is substantially spaced from the lower edge of the band B, and said cover is adapted to be detachably held on said band by means of a plurality of clips 4, 4, etc., which are of Z cross section and have horizontal portions 5 with apertures 6 therein, through which the lower ends of the screws A are adapted to be inserted at a point above the nuts N. Said clips also have continuing vertical portions 7 and horizontal extensions 8 extended outwardly therefrom.

The portions 8 are adapted to overlie the annular flat portion 3 of cover C, and are provided with apertures therein similar to the apertures 6 in the portion 5, which are

adapted to receive pins 9 riveted to the portion 3 of the cover. Portion 8 of the clips 4 also carry on the upper sides thereof locking members 10 which are riveted at 11 to the clips and are adapted to be frictionally held in slots 11' formed in the peripheries of the pins 9 for retaining the cover in operative position on the banjo. The locking members 10 have vertical extensions 10' on the outer ends thereof by means of which said members may be operated for locking and unlocking the cover.

It will be noted that the cover C is provided with one or more series of apertures 12, 12, etc., which are arranged in ornamental and geometrical form, and additionally serve to provide means whereby the vibrations from the interior of the instrument may have free egress.

20 The outer side of the cover C in the center is provided with a concave portion 13 which receives the head 14 of an adjusting screw 15. Said screw has a reduced extension 16 which is threaded into the head 14 and which is reversely threaded from the stem 15 of the screw. Intermediate the portions 15 and 16 said screw has an enlarged shoulder 17 which engages the central portion 18 of the cover and is also provided with a portion 16' held in the opening of the cover. On the interior of the portion 19 of the resonator a concave reinforcing member 20 is welded for providing additional thickness at this point to receive the screw 15.

35 The screw 15 carries a coil spring 22 therearound which is adapted to compress between the portion 17 of the screw and the portion 19 of the resonator, and the ends 23 and 24, respectively, of said spring are preferably held in openings in the portions 19 and 18 respectively of the resonator and the cover, so as to prevent the dislodgement of the spring.

45 The resonator is substantially of the same diameter of the body band B, or larger if desirable, and as shown in the drawings, it will be noted that the resonator is at all times held in spaced relation from the band B and may be adjusted relative to the cover C. By means of the adjusting head 14, the screw 15 may be turned for adjusting the resonator relative to the cover C, for the purpose of regulating the tone. The screw also serves to support the resonator resiliently in position and in such a manner that the same may be readily attached and detached at will.

55 Cover C is provided with an annular shoulder C' which underlies the outer portion of resonator R so that the edge of the resonator may rest upon said shoulder, as shown in Fig. 2. Thus, the adjusting screw 15 may be operated for adjusting the tension of the resonator against the cover for regulating the tone of the instrument, or if de-

sirable the resonator may be adjusted so as to completely disengage from the cover. In either case the spring 23 serves as a cushion for the resonator so as to hold the same spaced from the cover to a desired extent, 70 and thus prevents the rattling of the resonator against the cover due to the vibrations set up when the instrument is being played. The tone vibrations have free egress through the apertures 21 on the upper portion 3 of the cover. When the instrument is assembled the clips 4 are placed on the lugs L and underneath the nuts N, whereupon the skin S is tightened to a sufficient extent, and thereafter the cover is snapped into position under the portions 8 of the clips and locked by means of the locking members 10.

80 It will be obvious that the number of the screws A is immaterial and that this number may be more or less than that shown, also that it is unnecessary to support the cover C on the band B at a great number of points. Usually only three or four points of suspension will be necessary for effectively holding the cover and resonator in position on the band B, so that the clips 4 provided for holding the cover in position will necessarily be provided only for a desired number of screws A which are to be utilized.

85 What I claim is:

1. A banjo having a circular body portion, a skin closing one edge thereof, a metallic resonator supported in spaced relation from the opposite edge thereof, and a metallic cover forming a support for said resonator and detachably held on the exterior of said body portion, said cover having a diameter substantially larger than said body.

100 2. A banjo having a circular body portion, a skin closing one edge thereof, a metallic resonator adjustably and detachably supported on and spaced from the opposite edge thereof, and a metallic cover forming a support for said resonator and detachably held on the exterior of said body portion, said resonator being substantially of the diameter of said body portion, and said cover being of greater diameter than said resonator and said body.

110 3. A banjo comprising an annular body member, a skin stretched over one side thereof, an integral metallic cover attached to and substantially larger in diameter than said body, forming a back spaced from said body, and a metallic resonator overlying the body and mounted at a single central point on said cover, as described.

120 4. A banjo including an annular body portion, a membrane drawn over one side of said body, an integrally formed metallic cover closing the other side of and spaced from the edge of said body, and a metallic resonator mounted on said cover at a central point and disconnected from said body.

5. A banjo including an annular body portion, a membrane drawn over one side of said body, an integrally formed metallic cover closing the other side of and spaced from the edge of said body, a metallic resonator mounted on said cover at a central point and disconnected from said body, and means for adjusting said resonator.
6. A banjo comprising an annular body member, a membrane drawn over one edge

thereof, an integrally formed metallic cover comprising a rim portion of arcuate cross section, detachably supported on and extending outwardly from and around said body, a central web portion forming a back spaced ¹⁵ from said body portion, and a sheet metal resonator adjustably mounted at a central point on said cover and having its edge disconnected from the body.

JOHN DOPYERA.
